United States Patent Office

Des. 185,647
Patented July 7, 1959

185,647

MODEL TRAIN TRANSFORMER OR SIMILAR ARTICLE

David Rabinow, Cheshire, Conn.

Application February 9, 1959, Serial No. 54,524

Term of patent 14 years

(Cl. D26—14)

Fig. 1

Fig. 2

Fig. 3

Fig. 4

Fig. 1 is a perspective view and Figs. 2, 3 and 4 are respectively, front, side and plan views of a model train transformer, showing my new design.

I claim:

The ornamental design for a model train transformer or similar article, substantially as shown.
